UNITED STATES PATENT OFFICE

2,269,750

LIPSTICK

Donald F. Baird, Portland, Oreg.

Application March 21, 1940, Serial No. 325,093

1 Claim. (Cl. 240—6.46)

This invention relates to improvements in lipsticks, and more particularly to means for illuminating the same and the face of the user so that the lipstick may be useful in the dark. One of the principal objects of the invention is the provision of illumination for the entire face, and more brilliant illumination particularly for the lips of the user.

A further object is the provision of switch-actuating means which will prevent unintentional burning of the illuminating means when the stick is not in use and is carried or moved about in the handbag or carrying case of the user.

A further object is the provision of means for illuminating an area below the base of the lipstick proper and the projection of light around and beyond the lipstick.

A further object is the provision of a lipstick of this character which is of simple, efficient, durable, inexpensive and lightweight construction.

These and other objects will appear as my invention is more fully hereinafter described in the following specification, illustrated in the accompanying drawing, and finally pointed out in the appended claim.

In the drawing:

Figure 1 is a view of the invention illustrating one of its uses.

Figure 2 is a side elevation of the invention illustrating the means for preventing accidental or unintentional operation of the switching means.

Figure 3 is a view similar to Figure 2 with parts removed and broken away for convenience of illustration.

Figure 4 is a top plan view of Figure 5.

Figure 5 is a sectional view taken on the line 5—5 of Figure 4.

Figure 6 is a top plan view of a modified form of the invention.

Figure 7 is a sectional view taken on the line 7—7 of Figure 6.

Referring now more particularly to the drawing:

The main body 1 of the invention is of hollow cylindrical form, and made of any suitable opaque material, closed at one of its ends and internally threaded, as at 2, at its opposite or open end. The source of electricity, such as a dry battery, 3 is disposed within the housing 1. A lamp 4 is yieldingly supported above the battery 3 by a spiral spring 5 whose one end engages the base 6 of the lamp and whose opposite

end contacts the negative side 7 of the battery 3. The contact 8 at the end of the base 6 is normally held apart from the positive contact 9 of the battery by the spring 5.

5 A closure 10 of translucent material is provided for the open end of the housing. The lower portion of the closure 10 is shouldered, as at 11, to provide a reduced portion which is externally threaded, as at 12, for engagement with the internally threaded portion 2 of the housing 1 so that, as the closure is advanced on its threads, the lamp 4 will be caused to glow when its contact 8 is moved against the contact 9 of the battery. The bulb portion of the lamp 4 is always 15 in contact with the end wall of the closure 10, as shown, so that the lamp may be forced downwardly or allowed to move upwardly by advancing or retarding the cap on its threads.

To prevent accidental or unintentional closing of the circuit between the battery and the lamp, I form cooperating shouldered portions 13 and 14 on the abutting ends of the housing and closure, respectively. The closure may be freely advanced on its threads toward the housing in 20 the usual manner until the shoulder portions 13 and 14 come into frictional contact with each other, which will resist further rotation of the closure with respect to the housing. Then, further and more forceful turning of the closure 25 is required to disengage the shoulders 13 and 14 to allow the closure to finally move into circuit-closing position.

The upper end of the closure is provided with a hollow cylindrical projection 15, slotted as at 35 16, and slidably embraces the lipstick 17 carried by the base 18 which is slidably mounted within the projection 15. A lug 19 is formed integral with the base 18 and is slidably embraced by the slot 16 for convenience in projecting and retracting the lipstick with respect to the cylindrical projection. In the preferred form of the invention, illustrated in Figure 3, the closure, as 40 well as the extension 15, are made of translucent material, and a cap 20 of opaque material is provided to fit over the projection 15 and to bear against the top wall of the closure 10. When the cap is in place the light is allowed to project only out through the side walls of the closure. Thus, the device is useful as a portable light 45 for the interior of hand bags, and the like, and is generally useful otherwise. With the cap removed, of course, the light projects through the closure as well as the cylindrical projection.

50 In the modified form of the invention, illustrated in Figures 4 and 5, the end wall 10A of

the closure may be formed with cutout portions 21, or these portions may be made of clear or transparent material so that the light will be projected upwardly in cylindrical shape around the lipstick and direct a bright clear light in advance of the lipstick.

In the further modified form illustrated in Figures 6 and 7 the closure 22, its end wall, the cylindrical projection 23 and its inwardly extending ribs 23A for slidably supporting the lipstick, are made entirely of translucent material, but the projection 23 is of greater inside diameter than the outside diameter of the lipstick 24 and its base 25 to provide spaces 26 around the lipstick so that the light from the bulb 27 may be projected upwardly around the lipstick, and forwardly in advance thereof. In this form of the invention the projection 23 is slotted, as at 28, to slidably embrace a projection 29 on the base of the lipstick to provide convenient means for projecting and retracting the lipstick.

While I have shown a particular form of embodiment of my invention I am aware that many

minor changes therein will readily suggest themselves to others skilled in the art without departing from the spirit and scope of the invention. Having thus described the invention, 5 what I claim as new and desire to protect by Letters Patent is:

An illuminated lipstick comprising, a housing, a source of electricity and a lamp disposed within the housing, a closure of translucent material rotatably mounted on the end of the housing and adapted upon rotation to energize the lamp, a cylindrical projection formed on the closure and having inwardly projecting ribs to slidably embrace a lipstick, the lipstick being of lesser diameter than the inside diameter of the cylindrical projection to provide spaces around the lipstick through which the light from the lamp may be projected, and said cylindrical projection being slotted to receive a projection formed on the lipstick for extending and retracting the same with respect to the cylindrical projection.

DONALD F. BAIRD.
